UNITED STATES PATENT OFFICE.

HORACE MARGOTTA, OF SCRANTON, PENNSYLVANIA.

RAILWAY SIGNAL SYSTEM.

1,837,935.

Specification of Letters Patent.

Patented Apr. 20, 1920.

Application filed December 2, 1916. Serial No. 134,665.

To all whom it may concern:

Be it known that I, HORACE MARGOTTA, of Scranton, in the county of Lackawanna and State of Pennsylvania, have invented certain

5 new and useful Improvements in Railway Signal Systems; and I do hereby declare the following to be a full, clear, and exact description of the invention, such as will enable others skilled in the art to which it

10 appertains to make and use the same.

The object of this invention is to provide an improved system for automatically indicating on a moving car or train the condition of the rails, the presence on the same 15 track of cars or trains in the rear and in front traveling in the same direction, and also the presence of a car or train in front moving in the opposite direction, the latter condition being indicated on both cars or trains. Each 20 block of the track is divided into a series of sections with overlapping ends, and each car or train is equipped with contacts for engaging terminals of each section before and after leaving a section to indicate the 25 presence of a car or train forward or rearward. Each car or train is equipped with contacts for engaging terminals for electrifying the rails of forward sections through circuit-closers which are successively thrown 30 out of operation as the car or train progresses, and if a second car or train be moving in the opposite direction within the same block, the presence of each car or train will be communicated to the other.

35 In the accompanying drawings, Figure 1 is a diagrammatic view showing a series of sections. Fig. 2 shows diagrammatically the arrangement for indicating the presence in the section of a car ahead. Fig. 3 shows 40 the arrangement for indicating the presence of a car in the rear. Fig. 4 indicates the arrangement for electrifying sections in advance of a car whereby the presence of two cars moving in opposite directions may be 45 indicated. Fig. 5 is a view similar to Fig. 1, but indicating two cars in a block moving in opposite directions. Fig. 6 shows in detail a signal device on an exaggerated scale. Fig. 7 shows diagrammatically the contact 50 members carried by the car. Fig. 8 shows the arrangement for indicating broken rails.

In this description and in the claims the word "car" is to be considered the same as train of cars, but it is necessary that only 55 one car of a train be equipped in accordance with my invention.

Referring to the drawings, the main rails of a block are shown as divided into sections unsymmetrically, that is to say, the termination of a section in one rail is out 60 of line with the termination of the same section in the other rail, with the result that in passing from one section to another, wheels on a common axle will, for a short distance, be on rails of adjoining sections. 65 Intermediate the rails at end of section and between sections, are several terminals 2, 3, 4, 5^a, 6 and 8^a. The terminal 2 is located a short distance from the section to which it is electrically connected through terminal 70 8 by wire 7. This terminal 2 is intended to be utilized for indicating, to a train moving in one direction, the presence of a train ahead, and also the conditions of the track. The terminals in respect to a train moving 75 to the right in the several figures of the drawings are indicated by 2^a, 3^a, 4^a, 5, 6^a and 8.

The car equipment includes wheels 9 electrically connected through axle 10, the 80 positive pole of a battery W being connected to one of the wheels 9. The car carries a series of contact brushes 12, 13 and 14, (see Fig. 7) for engaging the several track terminals. These brushes are mounted on 85 axle 10 but insulated therefrom and from one another. Each of the contact brushes is designed to control signals on the train for indicating the conditions along the track.

Referring particularly to Fig. 7, the brush 90 12 is connected through suitable wiring with a positive pole of a battery W' and with the negative pole of battery W. In connection with this brush 12 is a relay 18 for controlling a signal lamp, preferably green, for 95 indicating the presence or indirectly, the absence of a car in a section ahead when the brush 12 engages terminal 2^a. The brush 12 is also designed to engage a terminal 5 or 5^a, according to the direction of the 100 train by which the presence of a car in the section ahead moving in an opposite direction will be indicated through a relay 17 upon engagement of the brush 12 with contact point 12', the signal lamp so controlled 105 being preferably red.

Brush 13, which I have shown in the form of a two arm lever, in its normal position is in engagement with the contact point 13' of the negative pole of battery W. This 110 brush is designed to be moved out of such engagement and into contact with contact

point 13² of a relay 16 which controls a third signal light, preferably blue, for indicating the presence or indirectly, the absence of a car to the rear traveling in the same direction, the contact between the brush 13 and the point 13' being broken when the brush 13 engages terminal 8.

Brush 14 is connected with the negative pole of battery W'. This brush is for the purpose of indicating the condition of the rails of the system, the engagement of the brush with the terminal 6^a making contact between the brush, which as before stated, is connected with the negative pole of battery W', and contact 14' of a fourth relay 17', such relay controlling a signal light, preferably white.

Referring now to Fig. 2, wherein a car, supposedly moving to the left, is indicated at X, and a second car, traveling in the same direction, at Z, before car X wholly leaves the section on which it is shown, and as it is to pass onto the next forward section, its contact brush 12 upon engaging terminal 2, which is connected through terminal 8 with the rail 1 in advance, will close the circuit through relay 18 if there is a car in the forward section, that is, the circuit will be completed through the wheels and axle of the forward car, and the presence of the latter will be indicated by the green light on car X. The circuit will be from the positive of battery W through the axle and wheel of the car at the right, rail 1', wheel, axle and wheel of car Z, rail 1, terminals 8 and 2, relay 18 to the negative of battery W. If, however, there is no car ahead in the same direction, relay 18 will not be energized, because of the absence of a carrying medium for the electrical energy between rails 1' and 1. If, at the same time, there is a car to the rear—in the section car X is leaving—that fact will be indicated on car X (see Fig. 3) through the closing of the circuit through relay 16 when contact is made between the brush 13 and point 13² by engagement of the brush with terminal 8^a, the circuit being established from the positive of battery W to the axle 10, wheel 9, of car X, rail 1, wheel axle and wheel of car Z, rail 1', terminal 8^a, brush 13, contact point 13², relay 16 to the negative of battery W.

At each station, or at each section, provision is made for automatically electrifying a sufficient number of terminals 5 in advance of a car to guard against the possibility of head-on collisions. The cutting in of the current to a single terminal is productive of the same result in respect to several such terminals in advance of the car. This is also true in respect of a car traveling in the opposite direction so that when the two cars are within the zone of their electrified terminals (5-5^a) signals of the approaching danger will be given on both cars. Each

terminal is separately controlled by circuit closers which are automatically positioned by cars traveling in either direction. Fig. 4 shows the terminals electrified by a car moving to the left.

As the battery circuit is closed through brush 13 and terminal 3 several forward circuit closers are operated and their respective terminals 5, being in circuit therewith, will close the circuit on the oppositely-traveling car when its respective brush 12 engages terminal 5, thereby causing a red signal on this car to prevent a head-on collision. The circuit established upon engagement of brush 13 with terminal 3 is as follows, (see Fig. 4): from the positive of battery W to the axle 10, wheel 9, rail 1', magnet 20, terminal 3, brush 13, contact point 13' to negative of battery W.

When brush 13 engages terminal 3, the electromagnet 20 will be energized, the negative pole of such magnet being connected to terminal 3, while the other pole is in circuit with the positive pole of the car battery through the track and wheel. When magnet 20 is energized it will actuate armature 21, and a circuit closing contact, the lead of which is indicated at 21', carried by, such armature will be brought into engagement with a contact 22 which is connected by a wire 23 with terminal 5. The armature 21 also carries second and third circuit closers, 24 and 24', which are insulated from each other. When armature 21 is actuated by its magnet it will be held in circuit closing position by engagement of its free end with the raised portion of the armature of a releasing magnet 28.

The circuit-closer 24 is designed to engage contact 26, which is connected by wire 27 with the rail of the next forward section. Circuit-closer 24' is intended to engage the contact point of an aerial wire 24'', which leads to magnet 20 of the next section through its terminal 3. A circuit will thus be established from magnet 20 through circuit closer 24, contact 26, wire 27, rail 1' to magnet 20, in advance, to terminal 3, aerial 24'', the contact point of such aerial, circuit closer 24', to the magnet. This circuit is effective to energize the magnet 20 of the next forward circuit closer, which in turn will operate a circuit-closer in advance and so until all the circuit closers of a section, or a sufficient number thereof, are actuated to avoid a head-on collision.

As each circuit-closer is operated its respective terminal 5 or 5^a is in condition to give the necessary signal through the brush 12 and contact 12' of the opposite car. The circuit for this signal is (see Fig. 5) from the positive of battery W to the axle 10, wheel 9, rail 1', wheel axle and wheel of the car at the left, rail 1, lead 21', contact 22, wire 23, terminal 5^a, brush 12, contact point 12', relay 17, to the nega-

tive of battery W. If the car battery is sufficient to cause the closing of the circuit through all of the circuit-closers of a block, as brush 13 engages the first terminal 3, there will be successive closings as a car advances.

During the travel of the latter it successively opens each of the circuit-closers, that is to say, after leaving a terminal 3 brush 13 10 will engage a terminal 4 to energize electro-magnet 28 and cause its armature to release the circuit closing armature 21, breaking the contacts 22 and also the circuit between the circuit closer 24 and 26 and contact 24' and 15 24''. One pole of electro-magnet 28 is connected to terminal 4 by wire 29, while the other pole is connected to the track, the circuit being thus established from the positive of battery W to the wheels and axle of the 20 car, the rail 1', lead 29', magnet 28, lead 29, terminal 4, brush 13 to the negative of battery W.

To insure the necessary indication of danger on both of the oppositely-traveling cars 25 the arrangement of electro-magnets and circuit-closers is duplicated on the other side of the track, and such are energized by cars moving in the opposite direction to that which has been assumed in respect of train 30 X, Fig. 4.

Thus, it will be seen that cars traveling in opposite directions will control each of a series of circuit-closers sufficiently in advance to insure signaling from one car to 35 another when two cars are traveling in opposite directions in the same blocks and that each of these circuit-closers is automatically deenergized by the car which caused its actuation.

40 In addition to indicating the presence or absence of a train ahead traveling in the same or in an opposite direction and a train in the rear, my invention also comprehends mechanism for indicating the condition of 45 the rails. Terminals 2 and 6 are employed for this purpose. Terminal 2 is connected with the beginning of main rail 1 (through terminal 8) and the end of this same main rail 1 by another wire is connected to the 50 armature 35 of a magnet 36 at the end of the section. This armature 35 when attracted by its magnet 36, will make contact with a ground wire 37. This magnet is energized simultaneously with the actuation of the 55 circuit closer through the same source of energy which actuates magnet 20. Terminal 6 is also grounded.

In the train there is energy W'. The negative pole of this energy goes to contact 14 60 and the positive through magnet 38 goes to contact 12. The circuit of this energy, then, will be completed when magnet 36 attracts its lever 35, the circuit being from battery W', magnet 38, contact 12, terminal 2, wire 65 7, terminal 8, rail 1, armature 35, ground 37,

terminal 6, contact 14, back to battery. The magnet 38 in the train will be electrified only when the above circuit is completed. Supposing, now, rail 1' will be broken, magnet 36 cannot be energized, and lever 35 will 70 not come in contact with wire 37, the rail 1' being the medium through which current is sent to the positive pole of the magnet 20 to which magnet 38 is connected.

If, on the contrary rail 1 will be broken, 75 the positive of energy W' cannot reach lever 35 of magnet 36. Therefore in both cases the circuit of energy W' will be broken, and magnet 38 will not operate on the train.

A relay 17' gives the signal for a broken rail. This relay depends entirely on magnet 38, and has a contact point 39 with which armature 40 of magnet 38 is in engagement save when the magnet 38 is energized, and a contact point 14'. Armature 40 is connected to the positive of the energy 80 W'. This contact 14' will come in connection with contact 14 when said contact 14 reaches the higher point of terminal 6, and then the negative of energy W' from contact 14 will run to contact 14', to the relay.

85 It appears from the above description that relay 17' will receive the negative of energy W' when and only when contact 14 comes in connection with contact 14'—the positive, on the contrary, only when magnet 38 is not energized. In other words, the circuit of the relay 17' is completed when the circuit of magnet 38 is broken. Therefore, the signal of broken rail is given because, as before explained, the circuit of magnet 38 will be broken, always, when one or both rails are broken.

90 Terminals 6 and 6^a are horizontal for about one-third their lengths, the remaining 105 two thirds being made in the form of an arch so that when contact 14, which passes over the terminal, reaches the highest point of this arch, it will come in contact with 14'. Contacts 5 and 8 and 5^a and 8^a are inclined 110 throughout their lengths for the purpose of effecting the necessary movement of the contact brushes to bring the relays into operation.

95 In the foregoing description reference has 115 been made in a general way to the signals on the car and their connections with the main battery. In Fig. 6 I have shown in greater detail the arrangement employed for a single signaling device. This arrangement is observed in respect to all the signals. The object in view is to maintain a signal even after the respective contact has left the terminal through which the signal circuit was closed. The signal selected for 120 illustration is that which indicates the presence of another train moving in the opposite direction. The positive pole of battery V of a secondary circuit is connected by a wire 55 to a lamp 56, by wire 57 to a bell 58 and 125 130

by wire 59 to an armature 60 of relay 17. The negative pole of battery V is connected by wire 61 to the core of the relay. The circuit of battery W (the main circuit) of 5 the car at the right, Fig. 5, is closed if another car moving to the right is present in the same section, when the brush 12 of the car moving to the left engages the terminal 5^a, the brush being moved into contact with 10 the point 12', the circuit being from the positive of battery W to the axle 10, wheel 9, rail 1, lead 21', contact 22 (connection between lead 21' and the contact 29 having been effected through the energization of 15 the magnet 20 by a car at the left in the manner hereinbefore described), wire 23, terminal 5^a, brush 12, contact point 12', relay 17 to the negative of battery W. When the circuit is so closed the relay will attract the 20 armature 60 which upon engaging the core of the relay will close the secondary circuit, causing the necessary signal through the bell and the light. To maintain the signal after the contact leaves the terminal, the 25 armature 60 carries a circuit-closer 62 which is insulated therefrom and connected by wire 63 to the positive pole of battery W, and when armature 60 is attracted by the relay, closer 62 engages a contact 64 which 30 is connected by wire 65 to a circuit breaker 66 which is normally in electric contact with a bracket 67 which is connected by wire 68 to relay 17 to which latter battery W is connected by wire 69. The contact 14 is connected by wire 70 to the relay. Thus the 35 circuit will be maintained through both batteries until it is broken by the engineer, and this is accomplished by moving the circuit breaker 66 out of engagement with 40 bracket 67.

The advantages of my invention will readily be appreciated by those skilled in the art. It is manifest that the extent of control exercised by each car equipped with 45 my improvements depends upon the conditions in each section of the road. One set of electro-magnets and a circuit-closer at each station may suffice under certain circumstances, but it may be necessary to have 50 several circuit-closers and magnets therefor between stations. Of course, these circuit-closers are only for the purpose of preventing head-on collisions. So far as concerns the other features of my invention, the automatic indication of the presence of a car 55 traveling in the same direction, ahead or in rear, these circuit-closers are not necessary.

I claim as my invention:

1. In an automatic signal, the combination 60 with a railway track divided into sections, of two series of circuit-closers, a series of terminals for operating a plurality of circuit-closers of a series in advance of a car, a second series of terminals controlled 65 by said circuit closers, a car having a source

of electric energy and contacts for engaging said terminals, and a signal on the car designed to be operated when the contact of a car is in engagement with one of the second series of terminals energized 70 through an oppositely-moving car.

2. In an automatic signal, the combination with a railway track divided into sections, two series of terminals, two sets of circuit-closers respectively controlling the 75 same, one set being controlled by cars moving in one direction and the other set by cars moving in the opposite direction, and terminals for each circuit-closer, one for closing a plurality of circuit closers of a 80 series in advance of a car and the other for opening the circuit closer with which it is connected, of a car having a source of electrical energy, two contacts in circuit therewith, one contact for engaging the last mentioned terminals for operating said circuit-closers, and the other contact for engaging a terminal of the first noted series, and a signal controlled by said latter contact. 85

3. In an automatic signal, the combination with a railway track divided into sections, a circuit closer for each section, two terminals for each circuit closer, one for closing it and a plurality of circuit closers in advance of a car and the other for moving it to open the circuit closer with which it is connected, and a terminal connected with each circuit closer and adapted to deliver signals to an approaching train, of a car having a source of electrical energy, 100 and a contact for successively engaging said two terminals. 90

4. In an automatic signal, the combination with a railway track divided into a series of sections, of two series of circuit-closers for said sections, each circuit-closer comprising an armature for closing the circuit between tracks of adjacent sections, terminals through which the circuit is closed for moving said circuit-closers in opposite 105 directions, means for causing a corresponding closing action in other forward circuit-closers as each circuit closer is successively closed, a terminal for each circuit-closer of the two series, a car, a contact carried by 110 the car for engaging one of the last noted terminals, and a signal controlled thereby. 115

5. In an automatic signal, the combination with a railway track divided into sections, of terminals for each section, two circuit-closers for each section each of which is connected to the respective terminal, electro-magnets for controlling said circuit-closers, means for successively energizing 120 said electro-magnets for opening and closing the circuit, means for communicating the closing action of each circuit-closer to one or more circuit-closers in forward sections of the track, a car having a source of 125 electrical energy, contacts for engaging said 130

terminals, and a signal designed to be operated by one of the contacts.

6. An automatic signal system comprising a railway track divided into sections, 5 electric terminals connected to the rails of each section and located some distance from the ends thereof, two series of circuit closers, terminals for each closer, one for closing a plurality of circuit closers of a series 10 in advance of a car and the other for opening the circuit closer with which it is connected, a terminal designed to be connected with a rail of a section in advance by one of said circuit closers, a car having a source of 15 electric energy, a contact in circuit therewith for engaging the terminals of one of said sets of circuit closers, separate contacts also in circuit with the source of electric energy designed to engage the terminals connected

20 with said rails and the terminal controlled by said circuit closers, and separate signals controlled by said last mentioned contacts.

7. An automatic signal system comprising a railway track divided into sections, 25 electric terminals connected to the rails of each section and located some distance from the ends thereof, an electric terminal adjacent said first mentioned terminals adapted to form part of an electric circuit, two sets 30 of circuit closers, terminals for each closer, one for closing and the other for opening the same, a terminal designed to be connected with the rail of a section in advance by one of said circuit closers, a car having 35 a source of electric energy, a contact in circuit therewith for engaging the terminals of one of said sets of circuit closers, separate contacts also in circuit with the source of electric energy designed to engage the 40 terminals connected with said rails, the terminal adjacent said rail terminals, and the terminal controlled by said circuit closers, and separate signals controlled by said last mentioned contacts.

45 8. An automatic signaling system including a railway track divided into sections, a circuit closer for each section, two terminals for each circuit closer, one for closing it and a plurality of circuit closers in advance of a car and the other for moving it to open the circuit closer with which it is connected, a terminal connected with each circuit closer and adapted to deliver signals to an approaching train, a series of electric 50 terminals adjacent said rail sections, a car having contacts for engaging said terminals, and signaling devices carried by the

car, each signaling device comprising a main circuit and a secondary circuit, said main circuit including a battery, a relay, an 50 armature therefor, a circuit closer carried by the armature, and contacts controlled by said circuit closer, said main circuit battery being adapted to close and open said 55 circuit closer of each rail section, and said secondary circuit including a battery and signaling devices, said latter battery being connected to said armature and said relay, and a circuit breaker in one of said circuits, and said main circuit battery being 60 also adapted to maintain said signaling devices.

9. An automatic signal system comprising a railway track divided into sections, 75 an electric terminal connected to the rails of each section at one end, a circuit closer connected to the opposite end of each of said rails, means for actuating said circuit closer, a grounded terminal adjacent said rail terminal, a car having a source of electric energy, a signal in circuit therewith, and means carried by said car including a contact designed to engage said grounded terminal for actuating said signal, and means also carried by said car for rendering said last mentioned means inoperative 80 through the instrumentality of said first mentioned terminal.

10. An automatic signal system comprising a railway track divided into sections, 90 an electric terminal connected to the rails of each section at one end, a circuit closer connected to the opposite end of each of said rails, means for actuating said circuit closer, a grounded terminal adjacent said 95 rail terminal, a car having a source of electric energy, a contact in circuit therewith and designed to engage said grounded terminal, a signal controlled by said last mentioned terminal, a circuit closer, a magnet 100 in circuit with said electric energy, a second contact in circuit with said magnet and designed to actuate the latter through the instrumentality of said rail terminal to render said signal controlling circuit inoperative. 105

In testimony whereof, I have signed this specification in the presence of two subscribing witnesses.
